DESIGN FOR A CORNER POST

Kenneth G. Downey, Malden, Mass.

Application June 10, 1933. Serial No. 48,366

Term of patent 3½ years

To all whom it may concern:

Be it known that, I KENNETH G. DOWNEY, a citizen of the United States, residing at Malden, in the county of Middlesex and State of Massachusetts, have invented a new, original, and ornamental Design for Corner Posts, of which the following is a description, reference being had to the accompanying drawing, forming a part thereof.

Fig. 1 is a side elevation;

Fig. 2 is a front elevation, and
Fig. 3 is a cross-section taken on the line 3—3 of Fig. 2.

I claim:

The ornamental design for a corner post substantially as shown.

Signed at Boston, in the county of Suffolk and State of Massachusetts, this 7th day of June 1933.

KENNETH G. DOWNEY.
